UNITED STATES PATENT OFFICE.

JULIUS J. GRUENFELD, JR., AND PAUL KIRCHER, OF CHICAGO, ILLINOIS, ASSIGNEES
TO MASSEY CONCRETE PRODUCTS CORPORATION, OF CHICAGO, ILLINOIS, A COR-
PORATION OF VIRGINIA.

POLE AND STEP THEREFOR.

1,369,098.

Specification of Letters Patent. Patented Feb. 22, 1921.

Application filed May 21, 1918. Serial No. 235,802.

To all whom it may concern:

Be it known that we, JULIUS J. GRUENFELD, Jr., and PAUL KIRCHER, both citizens of the United States, residing at Chicago, in the county of Cook and State of Illinois, have invented certain new and useful Improvements in Poles and Steps Therefor, (Case #1,) of which the following is a specification.

This invention relates to climbing devices for poles such, for example, as concrete poles.

One of the primary objects of our invention is the provision of an improved climbing device of the character described which can be used by linemen equipped with the ordinary spurs used in climbing wooden poles. Another object of the invention resides in the provision of a simple arrangement of concrete pole and step which can be shipped with the steps in place without liability of injury or breakage. Our invention also consists in so arranging the step with reference to the pole that the steps will not interfere with the use by linemen of certain special climbing devices in the nature of clamps which embrace and grip the pole. In general, our invention contemplates a simple and effective form of replaceable step which is economical to manufacture and capable of ready attachment or removal and which is so disposed with reference to the pole as to be protected from the effects of the weather, and which is of such a nature as to afford little or no assistance to an unauthorized person seeking to climb the pole.

We accomplish the foregoing together with such other objects as may hereinafter appear or are incident to our invention by means of a construction which we have illustrated in the accompanying drawings, wherein:

Figure 1 is a horizontal section through a hollow concrete pole showing our improved form of step in top plan; Fig. 2 is a side elevation of Fig. 1; Fig. 3 is a section taken on the line III—III of Fig. 2; Figs. 4 and 5 are end elevations of details of our invention; Fig. 6 is a partial section through a mold adaptable for use in forming the step receiving portions of the pole; Fig. 7 is a side elevation of the mechanism shown in Fig. 6; Fig. 8 is a section taken on the line VIII—VIII of Fig. 7; Fig. 9 is a section illustrating a modification of the devices shown in Figs. 6, 7 and 8.

Our invention is applicable for use in connection with hollow and solid concrete poles, and is shown in the accompanying drawings as applied to a hollow pole merely for convenience of illustration.

Referring now to the drawings, reference numeral 7 indicates the wall of the pole, there being formed in the outer face thereof, alternately on opposite sides, a plurality of step receiving recesses 8. The top and side edge walls 8^a and 8^b of the recessed portions are curved and the bottom edge wall 8^c is sloped as indicated in Figs. 1, 2 and 3, for a purpose which will hereinafter appear, while the bottom wall 8^d of the recess is flat, for reasons which will hereinafter appear. The apertures 9 are formed in the wall of the pole at each recessed portion 8 thereof, such apertures being located below the middle of such recessed portions. The apertures in the preferred form of our invention are square. The steps which we have indicated as a whole by the reference letter A are adapted to be inserted in the apertures 9, such steps comprising two members *a* and *b* so constructed and arranged as to constitute an expansion bolt whereby the steps may be securely but releasably held in position. The outer member *a* of the steps comprises a head 10 which is adapted to take against the bottom face 8^d of the recess, and a square shank 11 which is adapted to project into the aperture 9.

The head 10 is provided with a vertically disposed slot or aperture 12 which is flared at the top as indicated at 13 to more readily receive the spurs of the linemen. The head is also provided with a socket 14 adapted to receive the head of a machine bolt 15, such machine bolt being inserted by means of the aperture 16. The shank 11 is composed of a top leg and two side legs (see Fig. 4), the lower surface of the top leg being inclined as indicated in Fig. 3.

The second member *b* of the step constitutes a spreader which is composed of side legs 17 and a bottom leg 18 and a vertical wall 19. The spreader is in general form square but the top surfaces of the side wall 17 are inversely inclined with respect to the top wall of the shank 11. The front wall 19 is tapped and threaded to receive the machine bolt, such bolt having a loose fit in the socket 14.

From the foregoing it will be apparent that when the parts of the step are assembled and the machine screw tightened by the insertion of a screw-driver through the aperture 16, the spreader 7 will be drawn toward the head and the inclined surfaces described will cause the parts to spread or separate and jam in the aperture 9, thus securely but releasably fastening the steps in position.

10 The means for forming the recesses 8 and the apertures 9 will now be described, attention being directed to Figs. 6, 7, 8 and 9. In Figs. 6, 7 and 8 I have shown one form of apparatus for forming such recesses and apertures, such means comprising the mold form 20 from which the pole is made; the core block 21 which is adapted to form the recesses 8; and the plug 22 which is adapted to form the apertures 9. The core block 21 is preferably permanently attached to the form 20 by means of the screws 23 and it is provided with an aperture 24 adapted to receive the plug 22, such aperture being arranged in alinement with a similar aperture 25 in the wall of the form 20. The plug 22 is provided with a shoulder 26 adapted to limit the inward movement of the plug, the exterior or head portion of the plug being provided with a small aperture 27 adapted 30 to receive a cotter pin 28 which is passed through an aperture in the ribs 29 formed on the form 20. It is also provided with a second aperture 30 by means of which the plug may be removed.

35 The operation is as follows: The core blocks 21 having been secured to the wall of the mold form, the plugs 22 are then inserted to assume the position shown in Fig. 8 and they are then locked in place by means 40 of the cotter pin 28, such arrangement being particularly adaptable for use in following out centrifugal or rotary processes in forming the hollow poles. In the absence of some such locking means as the cotter pins, it will be apparent that the centrifugal force 45 will cause the plugs 22 to fly out. After the pole has been formed either by the rotary method or any other preferred method, the plugs 22 are removed, the arrangement being such that they strip out without ripping or 50 injuring the fresh concrete. After the plugs are withdrawn the mold form is stripped from the concrete pole.

In the modification shown in Fig. 9, instead of forming the plugs 22 separately, they constitute permanently a part of the core blocks 21.

The advantages of the improvement are as follows: The steps are so located in the recesses 8 that their heads are substantially flushed with the periphery of the pole, so that it is possible to ship the poles with the steps in position without any liability of breakage. This arrangement also has the 65 additional advantage that the steps will pre-

sent no interference to a lineman who is equipped with clamp climbers instead of with spurs. Furthermore the steps are protected from the effects of winter weather and are substantially non-freezing, and sleet 70 will not collect in the recesses because of the rounded surfaces or walls, and because the spur receiving apertures 12 are to a certain extent hooded over or protected by the walls of the recesses. It is also to be 75 noted that while the arrangement is such that the spurs of the lineman can be readily inserted into the steps, nevertheless the apertures and the steps are of such a size and so disposed that it will be exceedingly difficult 80 for an unauthorized person to climb the pole. Finally, it is to be noted that by forming the apertures 9 and the shank and spreader of a square shape, the steps will not turn but will always be held in proper 85 position to receive the spurs. In case of breakage it will be apparent that the steps may be readily replaced.

We claim:

1. A device of the class described comprising a pole having a recess in the face thereof and an opening in the bottom of said recess, and a step comprising a portion adapted to engage said opening and a climbing head disposed in said recess, together with means for locking the step in the opening.

2. A device of the class described comprising a pole having a recess in the face thereof and an opening in the bottom of said recess, and a step comprising a portion adapted to engage said opening and a climbing head disposed in said recess, together with means for locking the step in the opening, said head being flushed with the surface 105 of the pole.

3. A device of the class described comprising a pole, an opening in the pole, a step, a shank on the step extending into the opening, a wedge coöperating with the 110 shank, and means for adjusting the wedge.

4. A device of the class described comprising a pole, an opening in the pole, a step having a head adapted to receive a spur, a shank on the step extending into the opening, a wedge coöperating with the shank, means for adjusting the wedge, and an aperture in the outside of the spur receiving head through which access to the adjusting means may be had.

5. A device of the class described comprising a pole, an opening in the pole, a supporting member, a wedge adapted to co-operate with the supporting member and the surface of said opening, said member 125 being shaped so as to prevent its rotation in the opening, and means for adjusting the wedge.

6. A device of the class described comprising in combination a pole having an 130

opening, and a step having a head and a shank, a wedge coöperating with said shank and means for adjusting said wedge.

7. A device of the class described comprising a pole having a step receiving opening, a step having a head and a shank, said head being provided with a socket, a wedge coöperating with said shank, and a screw

fitting in said socket and having threaded engagement with said wedge whereby the wedge may be adjusted.

In testimony whereof we have hereunto signed our names.

JULIUS J. GRUENFELD, JR.
PAUL KIRCHER.
